CONDUIT CLEANER

Burton J. Bollinger, 10232 Tinker Ave., Tujunga, Calif.

Filed June 1, 1964, Ser. No. 80,217

Term of patent 14 years

(Cl. D9—2)

FIG.-3

FIG.-4

FIG. 1 is a side view of a conduit cleaner showing my new design;

FIG. 2 is a bottom plan view thereof;

FIG. 3 is a perspective view thereof; and,

FIG. 4 is a top plan view thereof.

The dominant features of my design reside in the portions shown in full lines.

The broken line showing of the coiled wire is partially omitted in FIGS. 2 and 3 for convenience of illustration.

I claim:

The ornamental design for a conduit cleaner, as shown and described.
